Primary Examiner — Paula Greene(74) *Attorney, Agent, or Firm* — Fenwick & West LLP(57) **CLAIM**

The ornamental design for a mobile phone earphone, as shown and described.

DESCRIPTION

FIG. 1 is a front elevational view of a mobile phone earphone showing our new design, the cord drawn broken away for indeterminate length;

FIG. 2 is a rear elevational view thereof;

FIG. 3 is a left side elevational view thereof;

FIG. 4 is a right side elevational view thereof;

FIG. 5 is a top plan view thereof;

FIG. 6 is a perspective view thereof;

FIG. 7 is an enlarged partial view of "A" as shown in FIG. 1; and,

FIG. 8 is an enlarged partial view of "B" as shown in FIG. 1. Any broken lines in the drawings are included for the purpose of illustrating environmental structure and form no part of the claimed design.
